Inventor:
Hobart G. Arnold.

United States Patent Office.

HOBART G. ARNOLD, OF ROCHESTER, NEW YORK.

Letters Patent No. 90,913, dated June 8, 1869.

IMPROVEMENT IN SASH-LOCK.

The Schedule referred to in these Letters Patent and making part of the same.

To all whom it may concern:

Be it known that I, HOBART G. ARNOLD, of Rochester, in the county of Monroe, and State of New York, have invented new and useful Improvements in a Fastener or Lock for Window-Sash, of which the following is a full and exact description, reference being had to the accompanying drawings, making a part of the specification, and to letters of reference marked thereon, and of said drawings—

Figure 1 is a perspective view of the lock, as applied to the sash, and let in even with the face of it, with the bolt extended downward and outward, showing its position when the sash is locked. Letter I represents a slot or opening in the box for the nib A, by which the lock is worked; notch D is intended to hold the tumbler and bolt up, so that the sash may be left unlocked at pleasure.

Figure 2. Here the face of the box is off, showing the relative position of the different parts when the sash is locked down.

Figure 3 shows the lock reversed, also for two screws, so that it may be applied to the face of the sash or moulding when desired.

Figure 4 is a separate view of the tumbler.

Figure 5 is a lateral view of the same.

Figure 6 is a separate view of the bolt.

Figure 7 is a lateral view of the same.

Figure 8 is a view of the bolt and tumbler, as when the bolt is locked down, the pin n, slot B, point or projection O, all being in the position as shown in fig. 2, so that any pressure inwardly on the outer end of the bolt drives the lower end of the tumbler down, and point O against the end of flange R, (the latter being, as here made, a part of the box,) and holds it there, the weight of the tumbler also helping in the same direction; and as the slants or bevels all harmonize, or so nearly, any upward pressure on nib A will raise the tumbler, lifting point O, so that it will clear the end of flange R, and work with the bolt about as freely as though it was not intended to be locked down.

Figure 9. Here the tumbler is raised, so as to clear the flange R, above referred to. (See the different positions of slot B and pin n, in this and fig. 8.)

The nature of this invention does not consist in making a sash-lock, consisting of a box, bolt, and tumbler, and so as at pleasure to lock the bolt up, that being secured to me by Letters Patent, dated October 15, 1867, antedated September 17, 1867, and reissued December 31, 1867; neither in locking the bolt down, as there named; but in the particular mode or manner of locking and unlocking the bolt and tumbler down, as shown in the accompanying drawings and above explanations, whether the lock is made with or without notched plate.

Any one skilled in the art will be able to make and use my invention, by referring to the drawings and explanations as above given.

The advantages obtained by this mode of locking the bolt down over those in my patent above referred to, are in the perfect harmony with which all the parts work to produce the desired results.

In the former patent the upward pressure on nib A needs to be perpendicular, or nearly so, or the tumbler will often hold in the notch, and cause more or less inconvenience.

In this, that difficulty is entirely obviated, and the whole appears to work just as freely by the nib A as though they were not intended to be locked down; while the locking and unlocking seems to be perfect, and with no additional cost or complication whatever.

Having thus fully described my invention and its utility,

What I claim as new, and desire to secure by Letters Patent, is—

Slot B, in combination with pin n, point O, and flange R, or their equivalents, substantially as an improvement to my patent reissued December 31, 1867.

HOBART G. ARNOLD.
